INDUSTRIAL SHIPPING PALLET

Charles E. Griffin, Jr., High Point, N.C., assignor to
Burlington Industries, Inc., Greensboro, N.C.

Filed Oct. 18, 1974, Ser. No. 516,275

Term of patent 14 years

Int. Cl. D9—99

U.S. Cl. D12—53

Fig. 1

Fig. 3.

Fig. 2

Fig. 4.

Fig. 5.

Fig. 6.

Fig. 7.

FIG. 1 is a top plan view of an industrial shipping pallet showing my new design;

FIG. 2 is a bottom plan view thereof;

FIG. 3 is a cross-sectional view thereof taken along the line 3—3 in FIG. 1;

FIG. 4 is a side elevational view thereof as viewed from the bottom in FIG. 1;

FIG. 5 is a side elevational view thereof as viewed from the top in FIG. 1;

FIG. 6 is a side elevational view thereof as viewed from the left in FIG. 1; and

FIG. 7 is a side elevational view thereof as viewed from the right in FIG. 1.

I claim:

The ornamental design for an industrial shipping pallet, as shown.
